DOOR LOCK

Lewis J. Whitney, Springville, Utah

Application July 23, 1935, Serial No. 32,817

23 Claims. (Cl. 70—150)

This invention relates to locks and more particularly locks for closures and the like operable from either side of the closure for effecting securing thereof in closed position and when unlocked, permitting of manual release from either side.

The present invention contemplates the provision of a simple, pleasing and attractive, durable yet uncumbrous, easily assembled and mounted locking construction eliminating the necessity of specialized installation such as by an expert lock smith. The arrangement and assembly are such as to require several simple operations which are commonly familiar to the average layman, as will be more readily apparent from the detailed description.

Another salient feature of the present invention resides in the provision of a simply and easily controlled structure which may be quickly manually brought to locking or obstructing condition from either side of the closure and which may be readily manually released from such condition from the inner side of the closure by a simple operation and from the outside by an uninvolved key actuation.

A further feature of this invention lies in the provision of a lock controlling arrangement embodying an uncomplicated elemental structure requiring for rendering it effective and ineffective only a simple manual unidirectional movement either manually or through the medium of an implement preferably in the form of a key.

Still another important feature of this invention resides in the provision of an obstructing arrangement embodying tumbler features readily lending themselves to facile variations in operation requirement whereby they are readily adaptable to varying controlling implement or key biting arrangements or combinations especially for accommodation to a series of locking structures desired to be operated by a single implement or key.

Other and further aims and advantages will appear from the following detailed description of a preferred embodiment of my invention illustrated in the accompanying drawings in which:

Fig. 1 is a fragmentary section of a casing and closure in the present embodiment, a wall, jamb and door illustrating a longitudinal section through a locking structure embodying features of the present invention, the parts being shown in the locked or dogged position precluding operation from the outer closure side except by proper key;

Fig. 2 is a fragmentary section similar to Fig. 1

showing the parts in unlocked or undogged condition whereby the latching bolt may be manually operated from either side;

Fig. 3 is a fragmentary elevation section taken substantially along the line 3—3 of Fig. 1;

Fig. 4 is a fragmentary plan view of the spindle, tumbler and rollback assembly;

Fig. 5 is a section taken along the line 5—5 of Fig. 4;

Fig. 6 is a plan view of the tumbler setting sleeve arranged to be responsive to manual operation from the inner closure side to effect undogging or release of the locking structure;

Fig. 7 is a section taken along the line 7—7 of Fig. 1;

Fig. 8 is a fragmentary section taken along the line 8—8 of Fig. 1;

Fig. 9 is a face view of the strike or keeper; and

Fig. 10 illustrates an operating implement or key partly in section.

Referring now in greater detail to the drawings, I have illustrated a preferred embodiment of my invention as applied to a closure such as a door adapted to abut a jamb 12 of a suitable frame applied in an opening in wall 13. A lock case plate 14 is applied to the inner face of the door 11, there being provided in the door and extending thereinto a suitable square mortise 15 terminating at the free swinging edge of the door in a somewhat deeper, preferably circular mortise 16 accommodating a somewhat thickened end plate bolt guide or sleeve 17 extending laterally from case plate 14. End plate bolt guide 17

receives and guides therein the head 18 of a reciprocating latching bolt 19 maintained in sliding engagement with the inner face of case plate 14 at its inner end adjacent its tail by an angular guide plate 20, the base 21 of which is suitably secured to the inner face of the plate 14 as by means of screws 22 with its flange 23 passing through a longitudinal slot 24 dividing the tail of bolt 19 into two furcations 25 and 26 terminating in angularly disposed sections 27 and 28, respectively each formed with a laterally directed

terminal flange 29 and 30, respectively directed away from plate 14. Flange 23 is of T configuration with the head portion thereof overlying furcations 25 and 26 to cooperate with sleeve 17 in maintaining the tail of the bolt 19 in sliding contact with plate 14. Sections 27 and 28 are each also provided with bosses or projections 31 and 32 respectively laterally directed away from plate 14 and acting as stop abutments for a purpose to be more specifically hereinafter described.

Bolt head 18 is preferably hollow being formed with an angular keeper or strike engaging end portion 33 and a camming strike engaging face portion 34 of somewhat ogee sectional configuration being then directed rearwardly, forming web portion 35 and then laterally toward the body of the bolt, providing a substantially V-shaped strengthening wall 36. The latter is provided with a transverse opening 37 adjacent the bolt body to provide a passage for the reception of a flat strip 38 extending rearwardly in spaced relation to the tail portion of bolt 19 and having sliding bearing support through an opening 39 provided for this purpose in flange 23 of guide plate 20. Strip 38 is threaded through a coil spring 40 which serves to normally urge bolt 19 to projected condition, the spring being under compression between stationary flange 23 and wall 36 of the bolt head. Adjacent its forward end, strip 38 is bent to provide a substantially V-shaped end the terminus 41 of which passes through an opening 42 in end portion 33 adjacent the camming wall 34, the extreme end of terminus 41 being normally held in retracted condition within the outer face of portion 33 by a coil spring 43 threaded on the strip having one end abutting the inner face of portion 33 with the other end engaging the crotch or apex of the V formed in the strip. Openings 37 and 42 are enlarged to permit of lateral play of the strip portions passing therethrough for a purpose which will be pointed out hereinafter.

Plate 14 is provided with an integral outwardly extending cylindrical boss 44 formed with an inwardly directed end flange 45, the inner periphery of which loosely receives and provides a bearing for a sleeve 46 extending beyond both sides of plate 14 and formed at one end with an outwardly directed annular flange 47 enlarged to one side to provide a rollback part having two wings 48 and 49 adapted to engage with flanges 29 and 30 respectively of bolt 19. A coil spring 50 surrounds sleeve 46 and has one end seated against flange 45 with the other engaging flange 47 to normally urge sleeve 46 inwardly with respect to plate 14. To accommodate the consequent inwardmost disposition of rollback wings 48 and 49, flanges 29 and 30 are of substantial lengths as may be readily seen in Figures 1 and 2.

Disposed within sleeve 46 and extending through to beyond the outer face of door 11 is a preferably cylindrical knob shaft or spindle 51 which is suitably secured to sleeve 46 by a setscrew 52 passing through a reduced neck or flange 53 of a hollow cylindrical knob 54. Knob shaft 51 is formed with an axial bore extending inwardly for approximately half its length, such bore receiving a rod 56 the inner end of which has a cross-rod or pin 57 threaded therethrough which can be axially reciprocated relative to spindle 51 in a transverse slot 58. The outer end of rod 56 (the end disposed beyond the inner face of door 11) is provided with a reduced portion receiving thereon a convex based cup 59 secured thereto by riveting or peening of the protruding end of rod 56 as at 60. A coil spring 61 is disposed between the base of cup 59 and the end of spindle 51, thereby normally urging rod 56 together with pin 57 inwardly relative to shaft 51.

The outwardly directed end of spindle 51 is formed with an inward axial key receiving bore 62 which terminates short of the transverse slot 58 defining therewith a separating wall 63 having a reduced threaded axial bore receiving and threadedly retaining an outwardly directed axial key

guiding pin 64, the outer end of which is preferably disposed a substantial distance inwardly of the outer end of key receiving bore 62 so as not to be readily distinguishable from the outside. Spindle 51 is formed with an external reduced portion at its extreme outer end for a purpose to be explained. 5

Seated in a transverse bore provided in door 11 in substantial alignment with boss 44 is a lining sleeve 65 formed at its inner end with a flange 66 abutting the wall of mortise 15 adjacent the sleeve receiving bore, a portion of flange 66 having integrally formed therewith a laterally projecting stop or spacing extension 67, the length of which may be varied depending upon the thickness of the door and which, for the purpose of preventing marring of the inner door face, abuts the plate 14. The outer end of sleeve 65 is formed with a substantial inward flange 68, the bore of which receives a rotatable sleeve 69 having an enlarged inner peripheral flange 70 shaped to accommodate itself for self-centering engagement with sleeve 65 and its flange 68, the outer end of sleeve 69 protruding beyond flange 68 and slidably supporting the outer end of spindle 51 in its bore or internal periphery. Spacing extension 67 may be of one standard length for all doors in order to assure of maintenance of a uniform distance from flange 68 to plate 14 thereby providing for accurate adjustment of the key assembly 10 and eliminating the risk of otherwise possible misassembly. The passage of sleeve 65 through the door and for a substantial distance beyond the outer face thereof provides for doors of varying thicknesses. Experience indicates that at the 15 present time approximately 95% of doors employed in dwellings are 1 1/8" through at the stile. Thus only a slight extension of sleeve 65 beyond this standard thickness will readily accommodate the structure to slightly thinner or thicker doors 20 without variation of the size of parts. Of course, larger doors such as those employed in office buildings, schoolhouses, etc., may be readily provided for by larger lock structures inasmuch as all parts will require proportional enlargement. 25 The protruding portion of sleeve 69 receives thereon an axial flange 71 of an outer hollow cylindrical knob 72 having a reduced bore 73 having a sliding fit upon the external periphery of the extreme outer end of spindle 51. The spindle 51 has 30 a sliding fit with sleeve 69 and is provided with diametrically opposed longitudinal grooves 55 to accommodate and slidably receive the heads of pins 74. The shanks or stems of these pins extend through radial bores in sleeve 69 and flange 55 71 of knob 72, thus providing a rotary driving connection between spindle 51 and knob 72. Assembly of sleeve 69, pins 74 and knob 72 may be 35 readily accomplished by making one of grooves 55 slightly longer than the other. Thus sleeve 69 and knob 72 are united for simultaneous rotation at the same time axial movement of knob 72 is restrained by the opposed abutment of the ends of flanges 70 and 71 of sleeve and knob, respectively. Flange 70 of sleeve 69 is concentrically axially 40 grooved at 75, the reason for which will follow.

Thus far, it will be noted that by virtue of the arrangement described, spindle 51 may be axially translated or reciprocated relative to plate 14 and sleeve 65 with its associated sleeve 69 and knob 72, while it may be rotated by either inner knob 54 or outer knob 72. Obviously, the rollback and all internal parts of spindle 51 will rotate and reciprocate therewith. 45

Upon the periphery of spindle 51 adjacent 50

flange 47, there is disposed a ring 76 formed of a tube of springy metal, the ring having a plurality (six being illustrated in the preferred form although this number may be varied at will) of 5 longitudinally extending coaxially arranged fingers 77 each being preferably bent radially outwardly adjacent ring 76, thence extending axially along spindle 51 to a point adjacent its outward end, whence its is bent inwardly at 78 and again 10 axially, (see Fig. 4), the extreme end portion being inclined toward spindle 51 and, as shown in Fig. 1, terminating in abutting relation with the inner end flange of sleeve 69 defining groove 75. These fingers are set to have their extreme ends 15 normally seek a position in abutment with the periphery of spindle 51. Each finger 77 carries thereon a radially inwardly extending pin 79 which is preferably adjustably secured thereto by a screw 80 (see Fig. 2), whereby its position, 20 with respect to its finger may be varied in a radial direction relative to spindle 51. The screws 80 may be rotatably but not reciprocably mounted in each finger while the pins 79 may have tight threaded fits with their respective screws to maintain any adjusted position to which they may be 25 set. To provide for ready adjustability of the pins, they may be appropriately non-rotatably guided in their respective bores in any suitable or preferred manner. Obviously, any suitable con- 30 verse arrangement for accomplishing the same purpose may be employed. Each pin 79 extends inwardly sufficiently to have its inner end disposed in the key bore 62 so that pressure im- 35 posed upon such inner end will tend to spring the associated spring finger 77 radially outwardly away from the periphery of spindle 51. The pins are preferably arranged in axially staggered relation although this may be varied at will so as not to be in radial alignment. Ring 76 is suitably 40 secured to spindle 51 as by set screws 81 so as to revolve with such spindle. Disposed also upon the periphery of spindle 51 and slightly in advance outwardly of ring 76 is a sleeve 82, the inner end of which is anchored to rod 56 by the 45 cross-pin 57 whereby it may be axially recipro- cated with rod 56 relative to spindle 51. Sleeve 82 is seated upon spindle 51 between the bowed, spaced away portions of fingers 77 and is formed with axial slots 83 for the accommodation there- 50 through for relative radial and axial reciproca- tion of pins 79, the slots being of sufficient lengths to accommodate the aforementioned axial stag- gered arrangement of the pins. At its outer end, 55 sleeve 82 is formed with a beveled flange 84, as best seen in Fig. 6, which may be engaged under the bent portions 78 of fingers 77 upon relative axial outward reciprocation of sleeve 82, thus flexing the outer inwardly offset ends of the fingers radially away from spindle 51. Since rod 60 56 is normally urged inwardly by spring 61, sleeve 82 will normally be held in inward disposition by the abutment of pin 57 with the inner end wall of slot 58.

The extreme outer end of spindle 51 is made 65 concave at 85 so that in the locked condition thereof, as shown in Fig. 1, it will present a smooth coincident face with and conform to the inner face 86 of the radial flange of knob 72 for a purpose hereinafter explained.

An escutcheon plate 87 is suitably secured to 70 the outer face of door 11 and is disposed to embrace sleeve 65 more or less snugly.

Referring now more particularly to Figs. 1, 8 and 9, I provide a keeper or strike plate 88 formed 75 of a plate providing two lobes or ears 89 for added

strength about the securing screws 90 and provided with a bolt receiving recess 91 and a bolt camming surface portion 92 to engage the bolt and reciprocate it to retracted position upon slamming of the door 11. Strike plate 88 is preferably secured to jamb 12 at the outward end of a mortise 93 of sufficient depth to accommodate bolt head 18 in the extended latching position thereof and also a plate 94 of some suitable insulating material pivotally connected to the inner face of the strike plate by a hinge 95 adjacent the bolt engaging edge of the strike plate opening 91, this plate having adjacent the free swinging edge thereof and extending therethrough from the under side to the upper side, 15 the riveted ends of a wire loop 98. Hinge 95 is preferably of the spring type normally urging plate 94 to a position toward opening 91. Loop 98 is adapted to overly and, under hereinafter mentioned conditions, to engage and connect electrical contacts 99 connected by suitable electrical leads 100 conforming to fire underwriters' regulations to a suitable audible or visible or combined signal disposed at a convenient point in the abode of which door 11 is a part or to a remote watch- 20 man's, janitor's or police signal station.

The key 101 I prefer to employ with the preferred embodiment disclosed herein is in the form of a cylindrical sleeve 102 (see Fig. 10) the external diameter of which is sufficient to have 30 a freely sliding fit with bore 62, one end of the key being provided with an internal thread 103 whereby the key may be suitably attached by threading to the non-writing end of a pen, pencil or the like. I prefer such attachment since these 35 implements are generally carried in distinctive places such as vest or coat pockets or when carried in a purse are more readily distinguishable and more easily grasped as compared to the conventional flat key. The other end of the key is 40 spun or swaged into graduated peripheral axially spaced ribs, ridges or steps suitably chosen to properly cooperate with pin 79 irrespective of the rotational angular disposition of key 101 relative to the spindle 51. The operative or effective end 45 of key 101 is of course of sufficient internal diameter as to have a free sliding fit upon guide pin 64.

In operation, assuming the parts to be in the position in Fig. 2, with the extreme ends of fingers 77 disposed in groove 75, spring 50 recipro- 50 cates and retains spindle 51 in outwardly projected position whereby rollback wings 48 and 49 are disposed away from plate 14. At the same time, the extreme outer end of spindle 51 will project beyond the inner flange face 86 of 55 knob 72. In this position of the parts, outward projection of spindle 51 is limited by the abutment of flange 53 of knob 54 with flange 45 of boss 44. Thus rollback wings 48 and 49 while moved away from plate 14, are kept clear of 60 flange 66 of sleeve 65 and yet in engagement with flanges 29 and 30 of bolt 19. In this condition, should either knob 54 or 72 be rotated in either direction of rotation, one or the other of rollback wings 48 and 49 will engage its appropriate cooperating flange 29 or 30, and by camming action cause the bolt head 18 to be retracted from the keeper or strike against the pressure of spring 49 and the door may then be 65 opened. Upon release of the knobs and subsequent slamming of the door, the parts will again assume the position illustrated in Fig. 2.

Should it now be desired to alter the latching structure to a locking function, it may be simply and easily accomplished by either (1) an axial 70

inward pull upon knob 54 from the inner side of door 11 or (2) by pressure from the outer side of door 11 upon the concave end 85 of spindle 51. In either case, spindle 51 is reciprocated inwardly causing the extreme outer ends of spring fingers 77 to be retracted from groove 75. Upon withdrawal of these fingers from groove 75, fingers 77 will tend to seek and assume a position contacting the periphery of spindle 51 and when 10 completely withdrawn from groove 75 will be disposed in opposed relation to the inner flange of sleeve 69 defining groove 75. Upon relief of pressure upon the exterior end of spindle 51 or pull upon interior knob 54, spring 50 will 15 immediately urge spindle 51 outwardly. Since fingers 77 are now in contact with the periphery of spindle 51, the spindle will be retained in retracted position by the abutment of such fingers with the inner flange of sleeve 69 and the 20 axial immobility of such sleeve. At this time, the forward uniting continuous edge of rollback wings 48 and 49 will be in the position shown in Fig. 1 in close proximity to plate 14 and bolt 19 and in the path of reciprocation of and, 25 therefore, in coplanar relation with bosses or projections 31 and 32 so that any rotative movement imposed upon either knob will be blocked due to the irreciprocability of bolt 19. Thus the outside knob is dogged against effective retraction of the bolt.

It is, of course, obvious that in any practical embodiment, some lost motion will be found in the operating structure due to the requirement of allowance for tolerable working clearances. 30 It is my purpose to take advantage of such necessary clearances and resultant lost motion in the event excessive rotating force is applied to the knob 72 or an effort is made to force the bolt back from the exterior by the insertion of a thin blade to engage the camming face 34 of bolt 19 in warning an occupant of the abode where the lock is employed or in warning a person at a remote point who may be charged with the protection of property, by the employment of a signal operating arrangement. As will be readily seen from Fig. 1, any material movement of bolt 19 rearwardly with the parts in dogged condition, will cause the rear end of strip 38 to abut the forward edge of the rollback thus causing strip 38 to remain stationary while bolt 19 is moved. The forward angled end 41 of strip 38 will now be engaged by the forward edge wall 42 of the opening in wall 33 of the bolt head, causing the forward end of the strip to be cammed downwardly as viewed in Fig. 1. This will cause the thus projected end of strip 38 to engage plate 94 and swing it against the normal spring pressure of its hinge thereby placing loop 98 across contacts 99 whereby the signal circuit (not shown) will be closed. Upon relief of such excessive forces, the parts will again assume the position shown in Fig. 1.

If it is now desired to free the mechanism and to restore it to the condition of a purely latching structure, it may be accomplished from the interior by grasping the reduced portion of knob 54 between the fingers of the hand tending to pull the knob inwardly and imposing opposite pressure with the thumb upon cap 59 and stem or rod 56. This will cause sleeve 82 to reciprocate outwardly relative to spindle 51 whereupon the beveled flange 84 will engage fingers 77 by camming against the under sides of bent portions 78 causing flexion of the finger outer ends away from the periphery of spindle

51. The flange 84 is of course only of sufficient depth to cause enough elevation of fingers 77 to clear the inner flange of sleeve 69 defining groove 75 whereupon spring 50 will reciprocate spindle 51 outwardly until the outer ends of fingers 77 will abut the bottom wall of groove 75. The rollback will at this time be clear of projections or bosses 31 and 32 and the bolt may now be manually reciprocated from either knob.

Similarly, the change from locking to latching structure may be accomplished from the exterior by the insertion of key 101 into bore 62. Since the concave face 86 of knob 72 and the concave end 85 of spindle 51 present an unbroken contour, it will be readily apparent that the insertion of the key into bore 62 involves only the engagement by the key end of any portion of face 86 or end 85 whence a gentle push will be sufficient to cause the key to be guided into the key opening or bore. As the key proceeds further into key bore 62, the reduced end thereof is received upon the stem or guide 64. While this stem 64 is not necessary to the guidance of the key in bore 62 due to the concentric fit of key and bore, it is desirable as a bar to the insertion of solid cylindrical picking rods of a diameter similar to or slightly smaller than bore 62 and provides a substantial displacement reducer of bore 62 so as to limit the available space to other picking tools 30 adjacent the operating pins 79 thereby rendering tampering materially more difficult. As the key is driven home to the full depth of bore 62, pins 79 are radially displaced outwardly from bore 62 whereby spring fingers 77 will be similarly displaced away from the periphery of spindle 51. Such movement of fingers 77 will remove the free ends thereof from abutting contact with the end of the inner flange of 69 defining groove 75. Upon the ends of the fingers clearing this flange and their alignment with groove 75, spring 50 will cause the spindle 51 to be axially reciprocated outwardly whereupon the mechanism will assume the relationship and arrangement illustrated in Fig. 2. It will be readily apparent from the above that only a simple translational movement involving very little effort on the part of the authorized user, will effect quick and ready restoration of the parts to latching condition from locking condition. The key, having no other function than to displace pins 79, is thus materially simplified. It will be clear then that operation effort or pressure required is reduced to a minimum.

I desire to further call attention to the fact that the arrangement disclosed permits of a large number of combination variations as follows (1) the thickness of the inner flange of sleeve 69 defining groove 75 may be substantially varied; (2) the pins 79 may be displaced radially relatively to fingers 77; (3) all fingers should preferably be in contact with the periphery of spindle 51 when the structure is in locked condition thus rendering the structure less liable to response of unauthorized manipulation by the insertion of picking tools, although it will be readily apparent that the number of such abutting fingers may be varied at will; (4) the number of fingers may be varied by replacement of ring 76 with another ring having more or less than six fingers; (5) the relative positions of pins 79 upon fingers 77 may be changed; (6) the geometric shapes of either or both bore 62 and pin 64 may be altered; or (7) any combination or combinations at will may be employed. Such ready variation allows for the 75

employment of a large number of this type of lock in one building or in the same community. The ready replaceability of ring 76 and fingers 77 provides for tumbler changes requiring no material alteration of the locking structure. Since sleeve 69 is formed with groove 75 defined by inner and outer flanges, the latter will serve as an effective picking preventive, the size of groove 75 being limited and the outer flange serving as an abutment for the ends of fingers 77 should the latter be flexed outwardly too far by pressure of a picking tool upon any of pins 79 to the limit possible and beyond proper positioning of the finger ends beyond groove 75. Of course, any changes of contour of either or both bore 62 and pin 64 may be accompanied by accommodating changes to the key. Pin 64 may be eliminated and/or other impediments such as wards employed, although in the interest of simplified unidirectional movement of the key, I prefer to employ smooth guides.

Since pins 79 are readily adjustable, an important feature of the structure and arrangement resides in the fact that the operating combination of the fingers may be varied to accommodate a particular key. Thus, should it become necessary to replace the key for any reason, it is only necessary to vary the positions of pins 79 to cause fingers 77 to properly respond to the bitting of the new key. This eliminates the present requirement in conventional tumbler locks of accurate bitting of a new key involving considerable skill and renders key fitting a considerably less time consuming problem than heretofore. Obviously, a plurality of my devices employed in the various doors about a dwelling house may be readily arranged to respond to one particular key irrespective of the bitting combination. At the same time, inaccuracies in key manufacture may be readily compensated for by this arrangement thereby reducing the present requirement of accurate key bitting to certain set combinations and minimizing the necessity for manufacturing precision causing a substantial saving in this phase of lock manufacture.

Inasmuch as the key is tubular and its length may be varied, the cylindrical unbitted regular portion thereof may be employed for the application of identifying or advertising indicia imposed by stamping, pressing, engraving or in any other preferred or desired manner.

Thus, I have disclosed an operative preferred embodiment of my invention having the attributes enumerated in the introductory portion of this description.

As will be readily apparent to those skilled in the art, numerous changes may be made in my preferred embodiment within the spirit and scope of the appended claims and I, therefore, do not desire to be limited to the precise disclosure.

What I claim as my invention and desire to secure by Letters Patent is:

1. A lock for a closure comprising a normally projected bolt member, means for retracting said bolt member including a reciprocatory and rotary spindle, a rollback on said spindle and cooperating with said bolt member, knobs associated with said spindle for imparting rotation thereto, a portion of the spindle normally projecting through one of said knobs, one of said knobs having slidable connection with said spindle with the other having fixed connection therewith, cooperative means associated with said rollback and bolt member disposable in cooperative relationship to prevent retraction of said bolt member

upon reciprocation of said spindle by movement of its fixed knob or by force to the projecting portion of said spindle protruding from a portion of the other of said knobs, means to prevent reverse reciprocation of said spindle to release 5 said bolt member for operation by rotation of either knob, means associated with said fixed knob capable of releasing said spindle for reciprocation and rotation, and key-operable means accessible through the other knob to effect similar release.

2. A lock for a closure comprising a normally projected bolt member, means for retracting said bolt member including a reciprocatory and rotary spindle, a rollback on said spindle and cooperating with said bolt member, knobs associated with said spindle for imparting rotation thereto, a portion of the spindle normally projecting through one of said knobs, one of said knobs having slidable connection with said spindle with the other having fixed connection therewith, cooperative means associated with said rollback and bolt member disposable in cooperative relationship to prevent retraction of said bolt member upon reciprocation of said 25 spindle by movement of its fixed knob or by force to the projecting portion of said spindle protruding from a portion of the other of said knobs, releasable blocking elements movable to restrain return reciprocation of said spindle, and mechanism manually operable in association with said fixed knob to release said blocking elements whereby said spindle may be repositioned to render said rollback and bolt member cooperating means ineffective thereby permitting retraction 35 of said bolt member responsive to rotation of either of said knobs.

3. A lock for a closure comprising a normally projected bolt member, means for retracting said bolt member including a reciprocatory and rotary spindle, a rollback on said spindle and cooperating with said bolt member, knobs associated with said spindle for imparting rotation thereto, a portion of the spindle normally projecting through one of said knobs, one of said knobs 45 having slidable connection with said spindle with the other having fixed connection therewith, cooperative means associated with said rollback and bolt member disposable in cooperative relationship to prevent retraction of said bolt member upon reciprocation of said spindle by movement of its fixed knob or by force to the projecting portion of said spindle protruding from a portion of the other of said knobs, releasable 50 blocking elements movable to restrain return reciprocation preventing position of said spindle, and key operable means effective to release said blocking elements.

4. A lock for a closure comprising a normally projected bolt member, means for retracting said bolt member including a reciprocatory and rotary spindle, a rollback on said spindle and cooperating with said bolt member, knobs associated with said spindle for imparting rotation thereto, one of said knobs having slidable connection with said spindle with the other having fixed connection therewith, cooperative means associated with said rollback and bolt member disposable in cooperative relationship to prevent retraction of said bolt member upon reciprocation 65 of said spindle by movement of said fixed knob or by force to a portion of said spindle protruding from a portion of the other of said knobs, releasable blocking elements comprising spring fingers carried by said spindle and normally held 70

75

in inoperative disposition but responsive to reciprocation of said spindle to effect return reciprocation of said spindle thereby causing said cooperating means to prevent retraction of said bolt member, means normally urging said spindle in return reciprocation direction, and manually operable means associated with said fixed knob and effective to cause said fingers to assume non-blocking positions thereby permitting said spindle to be reciprocated by said urging means to cause dissociation of said cooperating means whereupon said bolt member may be released by rotation of either knob.

5. A lock for a closure comprising a normally projected bolt member, means for retracting said bolt member including a reciprocatory and rotary spindle, a rollback on said spindle and cooperating with said bolt member, knobs associated with said spindle for imparting rotation thereto, one of said knobs having slidable connection with said spindle with the other having fixed connection therewith, cooperative means associated with said rollback and bolt member disposable in cooperative relationship to prevent retraction of said bolt member upon reciprocation of said spindle by movement of said fixed knob or by force to a portion of said spindle protruding from a portion of the other of said knobs, releasable blocking elements comprising spring fingers carried by said spindle and normally held in inoperative disposition but responsive to reciprocation of said spindle to effect return reciprocation of said spindle thereby causing said cooperating means to prevent retraction of said bolt member, means normally urging said spindle in return reciprocation direction, and key operable means adapted to arrange said fingers in non-blocking condition whereby said spindle may be reciprocated in response to said urging means thereby effecting release of said cooperating means and freeing said bolt member for operation responsive to rotation of either knob.

6. A lock for a closure comprising a normally projected bolt member, means for retracting said bolt member including a reciprocatory and rotary spindle, a rollback on said spindle and cooperating with said bolt member, knobs associated with said spindle for imparting rotation thereto, one of said knobs having slidable connection with said spindle with the other having fixed connection therewith, cooperative means associated with said rollback and bolt member disposable in cooperative relationship to prevent retraction of said bolt member upon reciprocation of said spindle by movement of said fixed knob or by force to a portion of said spindle protruding from a portion of the other of said knobs, releasable blocking elements comprising spring fingers carried by said spindle and normally held in inoperative disposition but responsive to reciprocation of said spindle to effect return reciprocation of said spindle thereby causing said cooperating means to prevent retraction of said bolt member, means normally urging said spindle in return reciprocation direction, manually operable means associated with said fixed knob and effective to cause said fingers to assume non-blocking positions thereby permitting said spindle to be reciprocated by said urging means to cause dissociation of said cooperating means whereupon said bolt member may be released by rotation of either knob, and key operable means effective to alternatively cause said fingers to

assume non-blocking position to effect similar release of said bolt member.

7. A lock for a closure comprising a normally projected bolt member, means for retracting said bolt member including a reciprocatory and rotary spindle, a rollback on said spindle and cooperating with said bolt member, knobs associated with said spindle for imparting rotation thereto, one of said knobs having slidable connection with said spindle with the other having fixed connection therewith, cooperative means associated with said rollback and bolt member disposable in cooperative relationship to prevent retraction of said bolt member upon reciprocation of said spindle by movement of said fixed knob or by force to a portion of said spindle protruding from a portion of the other of said knobs, releasable blocking elements comprising spring fingers carried by said spindle and normally held in inoperative disposition but responsive to reciprocation of said spindle to effect return reciprocation of said spindle thereby causing said cooperating means to prevent retraction of said bolt member, means normally urging said spindle in return reciprocation direction, key operable means adapted to arrange said fingers in non-blocking condition whereby said spindle may be reciprocated in response to said urging means thereby effecting release of said cooperating means and freeing said bolt member for operation responsive to rotation of either knob, and means for adjusting said key operable means to vary the releasing movement necessary as desired to effect non-blocking disposition of said fingers.

8. In a lock of the class described, a reciprocatory and rotary spindle, an inside and outside knob arranged at the ends of said spindle, means associated with said spindle to prevent rotation thereof, means associated with said spindle permitting reciprocation thereof to prevent rotation thereof but preventing return reciprocation thereof to release said spindle for rotation, and manually operable means accessible from the inside end of said spindle to release said spindle return reciprocation preventing means.

9. In a lock of the class described, an axially shiftable and rotary spindle, a knob associated therewith at each end, means associated with said spindle adapted to prevent rotation of said spindle upon axial shift of said spindle, means normally opposing said shifting of said spindle, means responsive to axial shift of said spindle for overcoming said shift opposing means to block the return shifting effect of said opposing means, and means operable from either end of said spindle to effect release of said blocking means, whereby said spindle may be shifted to assume a position permitting rotation thereof.

10. In a knob lock, a supporting sleeve, an axially shiftable spindle carried by said sleeve, said sleeve having an axially directed groove in one end thereof defined by concentric flanges one of which embraces said spindle and presents an end edge, a plurality of spring fingers carried by said spindle upon its periphery and movable therewith, the free ends of said fingers normally seating in said groove, certain of said fingers being normally urged to contact the periphery of said spindle, whereby upon shift of said spindle and exit of the free ends of said certain fingers from said groove, said ends will be sprung to contact said spindle periphery and thereby assume a position in opposition to said sleeve end edge.

whereby return shift of said spindle is precluded 5 radially inwardly directed adjustable pins carried by said certain fingers having their free ends disposed in a bore in said spindle whereby said 10 certain fingers may be radially sprung outwardly to have their ends assume a position in alignment with said sleeve groove to permit return shift of said spindle, and a peripheral sleeve carried by said spindle and disposed between said 15 fingers and sleeve and shiftable axially along said sleeve to engage said certain fingers independently of said pins to return said displaced finger ends to alignment with said sleeve groove thereby allowing return shift of said spindle.

15. 11. In a knob lock, a supporting sleeve, an axially shiftable spindle carried by said sleeve, said sleeve having an axially directed groove in one end thereof defined by concentric flanges one of which embraces said spindle and presents an end 20 edge, a plurality of spring fingers carried by said spindle upon its periphery and movable therewith, the free ends of said fingers normally seating in said groove, certain of said fingers being normally urged to contact the periphery of said 25 spindle, whereby upon shift of said spindle and exit of the free ends of said certain fingers from said groove, said ends will be sprung to contact said spindle periphery and thereby assume a position in opposition to said sleeve end edge whereby 30 by return shift of said spindle is precluded, radially inwardly directed adjustable pins carried by said certain fingers having their free ends disposed in a bore in said spindle, an axially extending drill pin in said spindle bore, adapted to receive a key means disposable in said bore and upon 35 said pin comprising a tubular sleeve first receivable in said bore and then upon said pin, and having a plurality of reduced portions adapted to engage said radial pins to urge them radially outwardly sufficiently to cause said certain fingers 40 to be sprung outwardly in alignment with said groove whereby return shift of said spindle may be accomplished.

12. In a lock, a cylinder sleeve having an axially 45 directed ledge, an axially reciprocable sleeved member slidable in said sleeve, a plurality of radially movable elements carried by said sleeved member normally seated upon said ledge and urged radially toward said sleeved member 50 whereby to permit unseating of said elements upon reciprocation of said sleeved member to assume positions in opposition to the ledge edge next adjacent the external periphery of said sleeved member, and means associated with said elements 55 and extending inwardly of said sleeved member and protruding beyond the internal periphery of said sleeved member to be engaged by a key insertable into said sleeved member to cause said elements to be displaced radially outwardly and 60 out of opposition with said ledge edge to permit reseating of said elements upon said ledge.

13. In a lock, a bearing sleeve, a shiftable member arranged in said sleeve, blocking means carried by said member for engagement with said 65 sleeve to block movement of said member in one direction, said means comprising radially movable elements normally inaccessible from the exterior of said member, a key receiving way in said member, and radially directed elements having adjustable 70 connection with said movable elements and extending into said way for engagement by a key to shift said movable elements to ineffective position.

14. A locking device comprising a pair of 75 concentrically disposed relatively shiftable sleeves,

one of said sleeves projecting axially beyond the other, an abutment on one sleeve, a plurality of blocking elements on the projecting end of the other sleeve shiftable radially for engagement with the abutment to prevent relative movement of the sleeves in one direction, and means accessible in one of said sleeves for communicating radial movement to said blocking elements to allow movement of said sleeves in the said direction.

15. A locking mechanism comprising a bearing 10 sleeve, an axially shiftable shaft carried by said sleeve and terminating in an extension beyond said sleeve, an abutment on said sleeve in the direction of the extended portion of said shaft, means normally urging said shaft toward said 15 abutment, a plurality of peripherally spaced axially directed radially shiftable tumblers arranged to engage said abutment to preclude axial shift of said shaft in one direction, a key-way in said shaft, and radially inwardly directed elements associated with said tumblers and extending into said key-way whereby a key inserted in said key-way will impart radial movement to said tumblers away from said abutment to allow said shaft 20 to shift in the said direction. 25

16. A locking mechanism comprising a bearing sleeve, an axially shiftable shaft carried by said sleeve and terminating in an extension beyond said sleeve, an abutment on said sleeve in the direction of the extended portion of said shaft, 30 means normally urging said shaft toward said abutment, a plurality of axially directed tumblers carried by the external periphery of said extending portion of said shaft and having shiftable parts adapted to engage said abutment, a key-way 35 in said shaft, and pins on said tumblers extending into said key-way for access to a key whereby said tumblers may be shifted out of abutment engaging condition thereby freeing said shaft 40 for movement of the extending shaft portion toward said sleeve. 45

17. A locking mechanism comprising a bearing sleeve, an axially shiftable shaft carried by said sleeve and terminating in an extension beyond said sleeve, an abutment on said sleeve in the direction of the extended portion of said shaft, 50 means normally urging said shaft toward said abutment, a plurality of axially directed tumblers carried by the external periphery of said extending portion of said shaft and having shiftable 55 parts adapted to engage said abutment, a key-way in said shaft, pins associated with said tumblers for extension into said key-way for access to a key to impart radial shift to said tumblers, and adjustable connections between said pins and tumblers whereby the combination necessary to shift said tumblers may be readily varied.

18. For a lock mechanism, a resilient tumbler, and a key engaging part having adjustable association therewith to provide for variation of throw 60 necessary to render the tumbler ineffective in its blocking function.

19. For a lock mechanism, a flexible tumbler adapted for securing at one end and free movement at the other end, and adjustable key engaging means associated therewith for transmitting flexing force of a key to the tumbler, said adjustment providing for ready variation of the key contour which may be predetermined. 65

20. For a lock mechanism, a flexible tumbler 70 adapted for anchoring at a portion thereof, and a key-engageable pin having adjustable connection with said tumbler at a freely movable portion thereof, the pin being axially adjustable to accommodate predetermined key contours. 75

21. A lock of the class described comprising a reciprocatory and rotary spindle, with which said spindle is movably connected, an inside knob non-movably connected to said spindle, means controllable by movement of said spindle to provide for reciprocation of said spindle relative to said outside knob and restraining return reciprocation, and means within said inside knob adapted to effect release of said restraining means.
22. A lock of the class described comprising a reciprocatory and rotary spindle, with which said spindle is movably connected, an inside knob non-movably connected to said spindle, means controllable by movement of said spindle to provide for reciprocation of said spindle relative to said outside knob and restraining return reciprocation and axially shiftable means carried by said
- spindle and extending into said inside knob adapted to render said restraining means ineffective and thereby release said spindle.
23. A lock of the class described comprising a reciprocatory and rotary spindle, with which said spindle is movably connected, an inside knob non-movably connected to said spindle, means controllable by movement of said spindle to provide for reciprocation of said spindle relative to said outside knob and restraining return reciprocation, and a shiftable plunger normally urged to ineffective position disposed within said spindle and protruding into but encased by said inside knob having means for cooperating with said restraining means to effect release thereof from the inner side of said lock.

LEWIS J. WHITNEY.
